(57) **CLAIM**

I claim the ornamental design for a storm panel awning, as shown and described.

DESCRIPTION

FIG. 1 is a top front left perspective view of a storm panel awning showing my new design;

FIG. 2 is a top view thereof;

FIG. 3 is a front view thereof;

FIG. 4 is a rear view thereof;

FIG. 5 is a left side view thereof, the right side view being identical to the left side view;

FIG. 6 is a bottom view thereof; and,

FIG. 7 is a perspective view thereof, shown in its intended use, wherein the broken lines are shown for illustrative purposes only and form no part of the claimed design.
